APPARATUS FOR AND METHOD OF OBTAINING POWER FROM OCEAN WAVES

Application filed December 14, 1925. Serial No. 75,283.

Before describing in detail a suitable form of apparatus embodying my invention I will describe two fundamental principles which guided me in its development, and which are vital to the accomplishment of its general object.

First, it is a well established general principle of physics that the receiver of wave energy must be of the same order of magnitude as the waves being received. We have an illustration of this in the phenomena of sound where the object to receive the sound waves and reflect them back, as in an echo, must be at least several wave lengths wide. A more recent, and perhaps a better, illustration of the principle is in radio communication, where, in order to receive and convert the energy of the incoming waves to useful effect, we must have the electrical characteristics of the receiver of the proper magnitude to permit "tuning."

This question of the relative magnitude of the apparatus and the waves from which it is supposed to abstract energy is in fact the most important factor in the problem of recovering wave energy. This is one aspect of the problem that has been neglected in all prior attempts to recover energy from ocean waves, and my invention contemplates the practical application of this principle. I, therefore, propose in order to carry out the above principle and to achieve other results which will be described in detail hereinafter, to make my apparatus sufficiently long to extend across several waves.

As incidental to this first principle, it may be pointed out that, while floats and pontoons guided in various ways so as to pump air or water into tanks associated with the motor proper have been frequently proposed, no prior mechanism has included floats so arranged in series as to systematically and gradually convert the energy of the wave form as it passes underneath the series, and so constructed as to cause a minimum of interference with the natural stream lines of the water in which they are immersed, and to cause a minimum turbulence and throwing aside of the water.

In accordance with my invention the floats

are cylindrical in shape and they have a diameter approximately equal to the diameter of the circle described by the particle of water near the surface. They are arranged approximately perpendicularly to the direction of movement of the waves. They, therefore, cause practically no turbulence of the water, such as would occur with other shapes and they permit the form of the wave to proceed unbroken to the next and succeeding cells. No prior mechanism has included floats so disposed that the weight of the apparatus is unsymmetrically distributed over the wave form, the greater part of the weight falling upon the rising side. This action, which is known as "damping," is absolutely necessary if we wish to gradually bring the waves to rest and recover their energy.

The second fundamental principle is that no structure can be built on or near the shore strong enough to withstand the destructive action of the ocean waves at such a point, and that a successful apparatus must operate at a distance off shore, where the waves are larger and more uniform but much less destructive and where they have not already converted a large part of their energy into a more chaotic and destructive form of motion by reason of the comparative shallowness of the water.

In accordance with the invention I, therefore, propose to provide a mobile apparatus which is supported as an entirety on its own floats or pontoons. The apparatus may be located at a suitable distance away from the shore. With this type of construction in which the apparatus is of sufficient length to reach over several wave lengths, all of the parts acting and being acted upon can be placed in one integral structure which remains practically horizontal, thus getting the maximum amount of motion from the waves, and which may rise and fall as a whole with the tide.

The principal object of the invention is to provide an improved apparatus for converting the energy of deep sea or ocean waves into a usable form of energy, the said apparatus conforming to the foregoing principles and making use of a large number of floating cells or pontoons which support the appara-

tus and which rise and fall on the waves relative to the apparatus as a whole and thereby pump water under high pressure into a system of piping on the apparatus. The high pressure water may be used to operate a hydraulic turbine connected with an electric generator for generating electric current. The electric current may be used upon the apparatus or it may be transmitted to the shore by suitable means where it can be employed as desired.

A very important object of my invention, in addition to furnishing power, is to provide a place in the same apparatus (which may be mobile) for the immediate use of this power for the fixation of atmospheric nitrogen, for the manufacture of fertilizer and other nitrogenous compounds from the air and for other chemical manufacturing purposes. In accordance with the invention I may provide floating chemical manufacturing plants having abundant and cheap power for the production of valuable products and compounds from the elements obtainable in abundance from the sea and air or which may be taken to the apparatus from the shore.

Another object of the invention is to provide means whereby the apparatus as an entirety may be capable of self-propulsion, so as to maintain itself in the proper relation to the waves and to move from one location to another if desired.

Another object of my invention is to provide a structure that will gradually absorb the energy of the waves and act as a breakwater at certain places. The present method of protecting harbor and parts of the shore by building great walls of masonry is unscientific because these walls do not absorb the energy of the waves they merely reflect it back upon itself. This may cause a worse condition in so far as shipping is concerned. Furthermore, such reflection requires a sea wall of great strength. A structure built along the lines of my invention would be an "absorber" of this energy and it would not be reflected back but would be absorbed and converted into useful effect. In such service the invention would have to be anchored in a certain position; but it would be found that the amount of force necessary to hold it in position would be very small compared with the "impact" exerted against a solid wall, for the reason that it would remove the energy gradually.

Further objects of the invention are to provide certain improved structural and mechanical features as hereinafter fully set forth.

Still other objects will be apparent from the following specification and claims.

In the accompanying drawings I have shown one embodiment of the invention, but it will be understood that the drawings are for illustrative purposes only, and that va-

rious changes and substitutions may be made within the scope of the claims without departing from the spirit of the invention.

Of the drawings:

Fig. 1 is a diagrammatic plan view of an apparatus embodying my invention, many of the details of construction being omitted for the sake of simplicity.

Fig. 2 is a side view.

Fig. 3 is an end view.

Fig. 4 is a fragmentary plan view on an enlarged scale showing some of the features of construction in greater detail. In this view, however, the central power plant is not shown in detail inasmuch as it is so shown in another figure.

Fig. 5 is a fragmentary side view on the same scale as Fig. 4.

Fig. 6 is an end view on the same scale as Fig. 4.

Fig. 7 is a fragmentary view on a still larger scale showing the construction of one of the float units.

Fig. 8 is a side view of the parts shown in Fig. 7.

Fig. 9 is a fragmentary sectional detail view on a still larger scale, this view being taken along the line 9—9 of Fig. 7.

Fig. 10 is a fragmentary sectional detail view, this view being taken along the line 10—10 of Fig. 8.

Fig. 11 is a diagrammatic plan view on an enlarged scale showing the power plant.

Fig. 12 is a side view of the parts shown in Fig. 11.

Figs. 13 to 16 are diagrammatic views.

The apparatus, as a whole, comprises an open framework of structural steel or other suitable material, this framework being strongly constructed to resist flexure and being long enough to extend over at least two, and preferably more than two, waves of normal or average length. In practice the total length may be from 800 to 1000 feet.

Preferably the frame structure comprises a plurality of parallel trusses 1, 1 which extend through the entire length. These trusses are spaced at uniform distances apart, and are connected by suitable transverse members 2, 2 and 3, 3. Preferably, in order to stiffen the entire structure, I provide a series of longitudinal tension cables or rods 4, 4, supported on struts 5, 5 at the top of the structure; and I may also provide if necessary a series of tension rods 6, 6 supported on struts 7, 7 at the bottom of the structure. To provide additional transverse stiffness diagonal brace members 8, 8 may be provided extending diagonally downward from the tops of the several struts 5, 5.

Referring more particularly to Figs. 4, 5 and 6, it will be seen that each truss 1 is provided with upper and lower longitudinal members 9 and 10 between which extend a series of uniformly spaced vertical mem-

bers 11, 11. Diagonal brace members 12, 12 extend across the rectangles formed by the said members 9, 10 and 11 to brace and reinforce the structure.

The beforementioned transverse members 2, 2 are preferably located somewhat below the longitudinal members 9, 9. Each of these members 2, 2 preferably comprises two parts 2^a and 2^b which are located on opposite sides respectively of the corresponding vertical members 11, 11. Preferably diagonal brace members 14, 14 serve to connect the members 2^a and 2^b with the respective members 9 and 11. The beforementioned transverse members 3, 3 are preferably located adjacent to the bottoms of the members 11, 11 and are directly connected either with the said members 11 or with the longitudinal members 10, 10.

Preferably a deck 15 is provided, this resting directly on the longitudinal truss members 9, 9. This deck may extend over the entire structure or it may be provided only where needed for actual protection or use. If desired a lower floor or deck 15^a may also be provided. If the power developed is transmitted to the shore as hereinafter described, and no manufacturing is carried on upon the apparatus, both of these decks may be dispensed with.

The longitudinal spacing of the vertical members 11, 11 is preferably approximately the same as the transverse spacing of the trusses 1, 1. In practice this spacing may be from 12 to 15 feet or more depending upon the height and length of the waves. Between each pair of oppositely located vertical members 11, 11, there is provided a float 16 as shown more in detail in Figs. 7 and 8. Each float 16 is substantially cylindrical and is arranged with its axis horizontal and extending transversely of the apparatus. Each float is preferably formed of sheet metal, and it may be provided with circumferential corrugations for the sake of added strength. Each float is provided at each end with a suitable guide device, such as a roller 17, adapted to travel along a vertical guideway carried by the adjacent vertical member 11. As shown, particularly in Fig. 9, the members 11 carry vertical channel bars 18, 18 which are of such size as to receive the corresponding rollers 17. It will be observed that these guideways 18, in cooperation with the rollers 17, serve to guide the floats for vertical movements relatively to the framework of the apparatus. Preferably, for a purpose to be described, blocks 19, 19 are provided at the tops of the respective guideways 18, 18 to engage the corresponding rollers 17 and limit the relative upward movement of the rollers. These blocks 19, 19 are by preference readily removable. The lower ends of the guideways 18, 18 are closed as indicated at

18^a to engage the rollers 17, 17 and limit their relative downward movement.

Carried by the framework above each float 16 is a pump 20. Preferably this pump is carried by the corresponding two transverse members 2^a and 2^b. The pump 20 is preferably vertical and comprises a cylinder 21 which is open at the bottom and adapted to receive a vertically movable piston 22. Connected with the piston 22, preferably by a ball and socket joint at 23, is a connecting rod 24. A yoke structure 25 serves to connect the connecting rod 24 with the float 16. This yoke structure comprises diagonally extending members which, in cooperation with the connecting rod 24, assist in holding the float in a horizontal position as it rises and falls.

As shown in detail in Fig. 10, the cylinder 21 is provided with a normally closed inlet valve 26 and a normally closed outlet valve 27. The details of these valves constitute no part of the present invention and specific description is unnecessary. It will be clear that when the piston 22 moves downward with the float 16, it tends to draw fluid into the cylinder through the valve 26, the valve 27 at this time being closed. When the piston moves upward the fluid contained in the cylinder is forced out through the valve 27, the valve 26 at this time being closed. The cylinders and pistons are relatively small and, therefore, the pumps operate at high pressures. I contemplate the use of pressures ranging from 500 to 1000 pounds.

Suitably located on the framework, preferably near the center thereof, is a power plant station 28. Preferably the floor 29 of this station is located below the level of the deck 15. Two or more of the floats with their accessories may be omitted to provide room for the power plant station.

A system of high pressure pipes 30, 30 extends over the entire apparatus, and the various pipes of this system are connected respectively to the discharge valves 27, 27 of the several pumps 20, 20. The high pressure pipes 30, 30 communicate with a high pressure main 31 which in turn communicates through a valve 32 with a suitable fluid motor 33. The fluid used may be air or sea water, or it may be a separate body of water or water solution. If water, or a water solution, is supplied to the several pumps the motor 33 may be a hydraulic turbine. This turbine may be of the impulse type or of any other suitable type, and as the turbine itself does not constitute any part of my present invention, a detailed description thereof will be omitted. The hydraulic turbine 33 may be used to drive any desired apparatus requiring mechanical power, and as shown it is used to drive an electric generator 34.

A high pressure receiver 35 may be connected with the high pressure main 31, and 130

for the purpose of equalizing the pressure of the water delivered to the turbine.

If air or sea water is used the discharge from the motor or turbine may be wasted; but I prefer to use a non-corrosive liquid, such as a water solution of potassium bichromate. In the latter case the liquid discharged from the turbine 33 passes into a receiver 36 at low pressure from which it can pass through pipes 37, 37 which extend over the entire apparatus to the respective inlet valves 26, 26 of the several pumps 20. The provision for circulating a quantity of liquid instead of using sea water has the advantage that energy does not have to be expended in lifting the water from the surface of the sea up to the pumps a distance of fifteen or twenty feet. This energy could not be recovered with a turbine of the impulse type, which I propose to use. The non-corrosive solution can be conserved, and it will eliminate the corrosive action on the turbine wheel and on the cylinder and valve mechanism of the pump.

It may be found preferable to provide a pump 38 for withdrawing the liquid from the receiver 36 and delivering it to the pipes 37, 37 at a low pressure. In this way the pressure in the pipes is maintained at all times above atmospheric pressure, and there is no possibility of air entering the pipes in case there should be leaks at any points. As shown the pump 38 is driven by an electric motor 39.

Preferably a by-pass pipe 40, provided with a valve 41, extends from the high pressure main 31 to the low pressure system. The valve 41 may be opened to permit liquid to flow through the by-pass pipe when the valve 32 is closed to stop the flow of water to the turbine.

It may be found desirable to have a comparatively small opening 42 near the bottom of each float, and to provide an air supply system for the several floats to prevent any of them from filling with water through these openings, or through leaks that might develop. I have shown a system of pipes 43, which extend over the entire apparatus, and which are adapted to receive air under pressure from a suitable pump or compressor 43^a located in the power station. This pump or compressor may be driven intermittently and when necessary, or continuously, by means of a motor 44. From the system of pipes 42 suitable sections 45 of flexible hose extend to the respective floats 16. The hose sections do not interfere with the vertical movements of the floats, and serve to maintain a supply of air or other gas under pressure in the floats to maintain their buoyancy and prevent leakage as described above.

The system of piping and the maintenance of the buoyancy of the floats in the manner described serves another important purpose.

In certain cases it may be found desirable to use my invention to transmit high pressure water to the shore for elevated storage, for the generation of power, or for use in hydraulic mining. In such cases the apparatus would have no machinery on board, except the pumping cylinders and the high pressure receiver. By means of the aforementioned openings 42 in the bottoms of the floats, and the system of piping described, water could be permitted to flow into all of the floats, thus making the apparatus submersible. This would be resorted to only at times of extreme emergency, as it is well known that the movement of the water in wave motion falls off very rapidly with the depth below the surface. Suitable provision could be made for subsequently supplying air to the floats to force out the water and again bring the apparatus to the surface of the water.

It may be found desirable in some cases to provide the apparatus with means whereby it may propel itself through the water, or whereby it may at least maintain itself in the proper position to be acted upon by the waves. For this purpose, I have provided two propeller units located at one end of the apparatus and at the extreme corners thereof. When these propeller units are provided, the correspondingly located float units may be omitted. As illustrated, each propeller unit comprises a water tight casing or chamber 46, the bottom of which is below the lowest level of the water. A propeller shaft 47 projects rearward from the casing and carries a propeller 48. Located within the casing 46 is an electric motor 49 which is operatively connected with the propeller shaft, as for instance by means of a drive chain 50. It will be seen that when the two propellers 48, 48 are in operation the apparatus will be propelled through the water. Steering may be effected by momentarily stopping one or the other of the propellers as required.

Suitably located on the framework there is preferably provided a manufacturing station or plant indicated diagrammatically at 51 in Fig. 1. One or more of the floats with associated parts may be removed to provide room for the manufacturing plant. The manufacturing plant can be used for any desired or suitable line of manufacture, such as the fixation of atmospheric nitrogen for fertilizer, the electrolytic production of hydrogen and oxygen from water, the operation of the Haber process for making ammonia, the production of chlorine, caustic soda, bromine and other industrial products requiring power. Power to operate this plant 51 can be supplied directly from the said motor or turbine 33, but is preferably supplied electrically from the generator 34.

Referring to the diagrammatic Fig. 13, A and E can be considered as being any two floats in a series spaced apart by the distance

a or one-half a wave length. By reason of their own weights, these floats would be submerged in still or level water to the depths represented by the lines *b*. If these floats A and E be required to carry their proportionate share of the weight of the framework and associated parts they will have a greater submergence as represented by the lines *c* in Fig. 14.

If the water has a wave movement and if the waves have a length equal to 2^a , then a condition approximating that shown in Fig. 15 will result. The float E is shown as being at the crest of a wave, and the float A is being shown as being at the trough between two waves. The float A, being in the trough, is submerged only to the depth required to carry its own weight, and it does not assist in carrying the weight of the framework and other parts. The float E is submerged to an increased depth as represented by the line *d*, this increased submergence being necessary in order that the float E may carry an increased proportion of the weight of the framework and other parts which becomes necessary because of the fact that other floats, such as A, are not carrying their proportionate shares of the weight. Unless the height of the waves is greater than the vertical distance *e* between the lines *b* and *d* the floats will have no vertical motion and no pumping will take place.

Fig. 16 shows a series of floats A to I in the approximate positions which they may assume when acted upon by a wave. The float A is at the trough between two waves and is submerged only sufficiently to support its own weight. The float B has a greater submergence than the float A, but it is not quite submerged to the line *c*, and it therefore is not sufficiently submerged to be forced upward against the resistance offered by the liquid in the corresponding pump. The float C has been submerged somewhat beyond the line *c* and has, therefore, started to move upward thus forcing the corresponding piston into the pump cylinder, and forcing the liquid from the pump into the high pressure piping system. The float D has moved further upward and has done considerable work in forcing water into the high pressure pipes. The float E has reached the upper limit of its stroke, and has completed its work of forcing liquid into the high pressure system.

The float F has less submergence than the float E, but it has not moved downward for the reason that it is still submerged beyond the line *b*. It will be obvious that the float F can move downward only when it has approximately the amount of submergence that is required to carry its own weight, particularly if the pressure maintained in the supply pipes 37, 37 is approximately sufficient to open the valves 26. The float G has a submergence approximately to the line *b* and

has moved down a short distance. The float H has moved down a still greater distance, and the float I has reached the bottom of its stroke and is in a position corresponding to that of the float A. It is ready to begin another cycle of movement, and this will be repeated every nine or ten seconds, depending upon the length of the waves.

It will be seen that each float has a stroke *f* which is determined in part by the height of the waves, it being remembered, however, that this distance *f* is not equal to the height of the waves, but is approximately the height of the waves minus the height *e* already referred to in connection with Fig. 15. Calculations show that approximately one-tenth of the wave energy may be absorbed by one float, and if it be assumed that this relation continues to hold as the wave passes underneath a number of the floats, then a row of from twenty to twenty-five floats would absorb practically all of the energy capable of being absorbed. Bearing in mind the fact that successive portions of the energy are absorbed by successive floats it will be understood that it would be theoretically possible to provide an apparatus in which each successive float has a shorter range of motion than the preceding float. In actual operation, each successive float will have a shorter stroke, but for convenience and simplicity of manufacture I prefer to provide all of the floats with the same possible range of motion even though the floats toward the rear of the apparatus do not move through the entire range.

The shapes, sizes and relative positions of the floats are very important. The floats are cylindrical with their axes horizontal and extending transversely of the direction of movement of the waves. Each float has a diameter approximately equal to the diameter of the circle described by a particle of water near the surface. Each float is thus adapted to absorb the maximum amount of energy from the water, and to produce a minimum of agitation and turbulence in the water.

In view of the fact that the series of floats extends longitudinally over two or more wave lengths, it will be clear that the apparatus as a whole will remain substantially level. It will further be clear that the successive actions of the several pumps will serve to deliver a substantially uniform flow of fluid into the high pressure piping system.

In discussing the operation of the successive floats I have shown and referred to only a single longitudinal row of floats. It will be understood however that the floats in all of the rows act similarly, and that ordinarily all of the floats in any given transverse line will move upward and downward in unison.

It will be understood that in the operation of the apparatus the valves 32 and 41 must be so adjusted as to regulate the pressure

maintained in the high pressure system. If no resistance were offered to the pumps, the apparatus would go through its motions but no useful work would be accomplished, as this is accomplished only by delivering fluid under pressure. On the other hand, if the valves 32 and 41 were closed or approximately closed so as to build up an excessive pressure the entire apparatus would become 10 inoperative by reason of the pumps gradually becoming filled with liquid. Clearly if the pressure becomes so great that the pumps could not discharge against it the pumps would gradually become filled with liquid 15 and would collectively act to lift the entire apparatus above its normal position. The length of stroke of the various floats would gradually decrease until finally all of the floats come to rest in their lowermost positions. For the reason stated the valves 20 32 and 41 must be regulated to give the required operating pressure for the turbine, and at the same time to avoid an excessive pressure against which the pumps cannot act. It 25 will be thus seen that the action of the floats and pumps is to continually lift the superimposed structure out of the water and support it upon the high pressure water of the cylinders. Releasing this high pressure 30 water into the turbine permits the apparatus to descend. These two actions are in equilibrium when the apparatus is working normally.

In operating the apparatus, it will be 35 understood that it is to be initially towed or otherwise moved to a suitable distance from the shore, and that it is to be oriented so that its length will lie in the direction of movement of the waves. The floats will then 40 begin to move up and down in the manner already described, and if the low pressure supply system be primed the pumps will supply liquid to the turbine which in turn operates the electric generator. As soon as the apparatus is in operation it can maintain itself in 45 the proper position with respect to the waves by operating one or the other of the propellers so as to correct any tendency of the apparatus to drift into a position at an angle 50 to the direction of wave movement. It will further be understood that within certain 55 limits the apparatus can act to propel itself from one location to another, normally using both of the propellers, but stopping one or the other of them from time to time to effect steering.

A study of the mechanical construction of the apparatus will show that it is very simple, and that most of the parts are in multiple so that they can be made economically in large quantities. Most of the elements of the framework are duplicates of one another, and all of the floats, pumps &c. are identical in construction.

60 It will further be understood that the ap-

paratus is readily adapted for convenient maintenance and repair. Each float, together with the parts associated therewith, can be readily removed and lifted to the deck for inspection or repair. For this purpose, 70 the deck may be constructed with removable sections, and the several pipes may be provided with valves (not shown) whereby each pump can be separately shut off from the main system. 75

At the beginning of this specification, I mentioned the possible use of an apparatus embodying my invention for absorbing the energy of sea waves to prevent destructive action at the shore. For this purpose it may 80 be necessary to permanently locate the apparatus in fixed relation to the shore. The apparatus may be floating and permanently anchored, or it may be supported on a fixed structure extending outward from the shore 85 or upward from the bottom.

In some cases it may be preferable to conduct the power to the shore for utilization instead of utilizing it on the apparatus as 90 herein described. This may be done in suitable cases either by providing a pipe, with suitable flexible portions, extending to the shore and locating the hydraulic turbine on the shore, or it may be done by retaining the 95 turbine and generator on the apparatus and conducting the electric current to the shore for suitable utilization.

What I claim is:

1. In an apparatus for obtaining power 100 from waves, the combination of a rigid, open and unbuoyant framework having a length equal to or exceeding two wave lengths, a series of floats substantially uniformly distributed along the framework and serving as the sole means of support therefor, the said series comprising a plurality of parallel longitudinal rows and each float in the series being independently movable by the waves vertically with respect to the framework, and power mechanism on the framework connected to be operated by the relative vertical movements of the several floats. 105

2. In an apparatus for obtaining power 115 from waves, the combination of a main, rigid, open and unbuoyant framework, a series of floats each vertically movable by the waves independently with respect to the framework and each substantially cylindrical in shape and arranged with its axis horizontal and 120 approximately perpendicular to the direction of travel of the waves, the said floats serving as the sole means of support for said framework, and power mechanism on the framework connected to be operated by the relative vertical movements of the 125 several floats.

3. In an apparatus for obtaining power 130 from waves, the combination of a main, rigid, open and unbuoyant framework, bodily mov-

able so that it can be made to extend longitudinally in the direction of travel of the waves, a series of floats each vertically movable by the waves independently with respect to the framework and each substantially cylindrical in shape and arranged with its axis horizontal and approximately perpendicular to the direction of travel of the waves, the said floats serving as the sole means of support for said framework, and power mechanism on the framework connected to be operated by the relative vertical movements of the several floats.

4. In an apparatus for obtaining power from waves, the combination of a main, rigid, open and unbuoyant framework, having a length equal to or exceeding two wave lengths, a series of floats substantially uniformly distributed along the framework, the said floats being each vertically movable by the waves independently with respect to the framework and each substantially cylindrical in shape and arranged with its axis horizontal and approximately perpendicular to the direction of travel of the waves, and the said floats serving as the sole means of support for the framework, and power mechanism on the framework connected to be operated by the relative vertical movements of the several floats.

5. In an apparatus for obtaining power from waves the combination of a rigid open and unbuoyant framework, a plurality of buoyant floats movable by the waves independently of each other, the said floats acting as a sole means of support for said framework, a closed system of piping on the framework containing a substantially incompressible fluid circulated by the relative movements of the several floats.

6. In an apparatus for obtaining power from waves the combination of a rigid open and unbuoyant framework, a plurality of buoyant floats movable by the waves independently of each other, the said floats acting as a sole means of support for said framework, a closed system of piping on the framework containing a substantially incompressible fluid circulated by the relative movements of the several floats, means for restricting the flow of said fluid in the system, and means for recovering the energy stored in the fluid as a result of such restriction.

7. In an apparatus for obtaining power from waves and producing a dampening action thereon the combination of a rigid open and completely unbuoyant framework, having a length equal to or exceeding two wave lengths, a series of floats substantially uniformly distributed along the framework and serving as the sole means of support therefor, said floats being movable vertically with respect to said framework and independently of each other, each float being substantially cylindrical in form and arranged with its

axis horizontal and substantially perpendicular to the direction of travel of the waves, a circuitous system of piping on said framework containing a substantially incompressible fluid, means operable by said floats for producing a flow of the fluid in the circuit, means for restricting the flow of fluid in the circuit, and means for recovering the energy stored in the circulating fluid by the movements of said floats.

8. In an apparatus for producing a dampening action on waves the combination of a rigid open and completely unbuoyant framework having a length equal to or exceeding two wave lengths, a series of floats substantially uniformly distributed along said framework and serving as a sole means of support therefor, said floats being movable vertically with respect to said framework and independently of each other, each of said floats being substantially cylindrical in form and arranged with its axis horizontal and substantially perpendicular to the direction of travel of the waves, a circuitous system of piping on said framework containing a substantially incompressible fluid, means operable by said floats for producing a flow of said fluid in the circuit, and means for restricting the said flow through the circuit whereby the wave energy is absorbed by the fluid in circulation.

9. In an apparatus for obtaining power from waves the combination of a rigid open and completely unbuoyant framework, a series of hollow cylindrical submersible elements arranged with their axes horizontal and substantially perpendicular to the direction of movement of the waves each hollow element having a relatively and permanently open port in its bottom side, means on said framework for maintaining a gaseous fluid under pressure in each of said hollow elements whereby said hollow elements become buoyant and act as the sole means of support for said framework, a closed system of piping on said framework containing a substantially incompressible fluid said system including a series of vertically disposed pump cylinders secured to said framework and pistons carried by said hollow elements and operable respectively in said cylinders for displacing the fluid in said system when said hollow elements are moved by the waves relative to the framework, whereby a circulation of said fluid is effected in the circuit and the framework supported solely by the fluid between said pistons and the heads of said cylinders.

10. A method of obtaining power from ocean waves, which consists of subjecting each oncoming wave form to a succession of dampening operations at spaced intervals along the wave form, the sum of the intervals comprising a full wave length or more, and extracting a portion of the wave's energy at each interval, and thereby successively reduc-

ing the height of the wave proportionately as energy is extracted.

11. In an apparatus for recovering power from ocean waves, an unbuoyant weight solely and transiently supported at spaced intervals along the wave form by buoyant members vertically movable with respect to the weight, such buoyant members reacting transiently on the weight through the interposition of a fluid confined in a closed circulating system on the weight.

12. In an apparatus for recovering power from ocean waves, an unbuoyant weight solely and transiently supported at spaced intervals along the wave form by buoyant members vertically movable with respect to the weight, such buoyant members reacting transiently on the weight through the interposition of a fluid confined in a closed circulating system on the weight, and power mechanism on the weight connected in the said closed system and adapted to be operated by the pressure of the fluid in the system.

13. In an apparatus for recovering power from ocean waves, a rigid, open and unbuoyant framework solely supported by the transient and periodic reactions of a plurality of buoyant members movable with respect to the framework against a fluid interposed between the framework and the buoyant members and confined in a closed circulating system, said transient reactions occurring on the rising side of the wave form only and constituting the sole support of the framework.

14. In an apparatus for recovering power from ocean waves, a rigid, open and unbuoyant framework solely supported by the transient and periodic reactions of a plurality of buoyant members movable with respect to the framework against a fluid interposed between the framework and the buoyant members and confined in a closed circulating system, said transient reactions occurring on the rising side of the wave form only and constituting the sole support of the framework, and power mechanism on the framework connected in the said circulating system to be operated by the pressure of the fluid.
